MAGNETIC TAPE TRANSPORT

Harry F. Rayfield, Arcadia, and Magne Jarle Kjos, Du-
arte, Calif., assignors to Burroughs Corporation, De-
troit, Mich., a corporation of Michigan

Filed Mar. 25, 1966, Ser. No. 1,642

Term of patent 14 years

(Cl. D26—14)

FIG. 2

FIG. 1

FIG. 1 is a top front perspective view of a magnetic tape transport, showing our new design, the back being substantially a mirror image thereof; and

FIG. 2 is a left side elevational view, the right side being substantially a mirror image thereof.

The dominant features of my new design are shown in solid lines in the drawing. Portions of FIG. 1 are diagonally lined to indicate transparency.

We claim:

The ornamental design for a magnetic tape transport, as shown and described.
